UNITED STATES PATENT OFFICE.

JAMES H. PREATER, OF BROOKLYN, ASSIGNOR TO WRIGHT, GILLIES & BROTHER, OF NEW YORK, N. Y.

DESIGN FOR CANISTERS.

Specification forming part of Design No. 7,142, dated January 27, 1874; application filed January 17, 1874.
[Term of Patent 7 years.]

To all whom it may concern:

Be it known that I, JAMES H. PREATER, of Brooklyn, in the county of Kings and State of New York, have invented or produced a Design for a Canister, of which the following is a description:

In the annexed drawing, Figure 1 is a front elevation, and Fig. 2 is a sectional plan, of the said canister.

The general configuration of the sides *a*, back *b*, top *c*, and bottom is cubical; but the front upper portion is made as a segment of a cylinder, in which the cover *d* is introduced, as usual. The front *e* is flat, but with a raised frame, *f*, surrounding the same, and the general outline thereof is oblong, as seen in Fig. 1. At each side of the front piece *e* there is a recess formed by the concave or cylindrical segment *i*, uniting such front piece with the sides *a*. In the recess thus formed there is a

hood, *l*, that is a segment of an oriental dome, and beneath this is a base, *m*, upon which an image, *o*, may be placed.

I term this design for a canister a "pagoda;" but it will be evident that, where the images are omitted, the lower portion of the hood may be continued down to the base as a segment of a cylinder.

I claim as my invention—

The design of the shape and configuration of the segments *i*, at the sides of the front *e*, with the segments of a dome forming the hoods *l*, substantially as set forth.

Signed by me this 13th day of January, A. D., 1874.

JAMES H. PREATER.
